UNITED STATES PATENT OFFICE.

WILLIAM H. ELLIS, OF BOSTON, MASSACHUSETTS.

PILE-DRIVING DEVICE.

SPECIFICATION forming part of Letters Patent No. 760,859, dated May 24, 1904.

Application filed May 28, 1903. Serial No. 159,166. (No model.)

To all whom it may concern:

Be it known that I, WILLIAM H. ELLIS, a citizen of the United States, residing at Boston, in the county of Suffolk and State of Massachusetts, have invented new and useful Improvements in Pile-Driving Devices, of which the following is a specification.

This invention relates to improvements in pile-drivers, and has for its object to provide a pile-driving construction by means of which piles can be driven under water as well as on land, the hammer efficiently guided to fall in alinement with the pile, and piles of any required length driven to any desired point above or below the surface of the water.

In carrying out this invention I employ with a pile-driver an adjustable hammer guide or chute, which is substituted for the ordinary guideway between the uprights in a pile-driver, up and down which the hammer slides. The adjustable hammer guide and chute is placed in any desirable position between said uprights of the pile-driver and as the pile is driven is lowered till the desired position is attained for the depth at which the pile is to be driven.

Referring to the accompanying drawings, in which similar figures of reference indicate like parts, Figure 1 is a view in elevation of a pile-driver, showing the invention. Fig. 2 is a view in elevation, showing the hammer guide or chute. Fig. 3 is a transverse section thereof, on the line $\alpha\alpha$, Fig. 2. Fig. 4 is a detail view showing the construction of the hammer guide or chute. Fig. 5 is a detail view showing a modification of the hammer guide or chute.

In carrying out my invention I employ a pile-driver 1 of the usual form of construction, but omitting the slideways or guides for the hammer from the uprights 2. In connection with this pile-driver 1 I provide a hammer guide or chute 3, of any suitable construction, and adapted to be located in adjustable position between the uprights 2. The hammer guide or chute is preferably constructed as follows: It is made up in sections 4, of any suitable length, fastened together. Each section as here shown consists of four angle-irons 5, arranged at the corners of a

square, and held in this position by being secured by rivets 6 to transverse flanged plates 7. The angle-irons 5 are braced by means of crossed metallic strips 8, secured together and to the angle-irons 5 by rivets 6. The sections 4 are fastened together by bolts and nuts 9, engaging the flanges 10 of the plates 7. As many of the sections 4 are employed as are necessary to form a chute of the required length. In the foregoing construction the angle-irons 5 of the sections 4, abutting end to end, form the slideways or guides for the hammer. As here shown a hammer 11 of square shape is employed, which is adapted to slide between the angle-irons 5 and is provided with an extended portion 12, which is secured at its end to a wire rope 13, passing over a pulley 14 to a hoisting-drum. (Not shown.) The hammer guide or chute is not necessarily of a square shape, but may be formed with two or more slideways for the hammer, according to the shape of the latter, to adapt it to the chute. The lower end of the chute 3 is secured by cross-bands 15, riveted to the angle-irons 5. In order to readily introduce the hammer into the chute 3, its upper end is preferably formed with an enlarged or flaring-shaped top 16, constructed with the inclined strips 17, fastened together at their upper ends by the riveted bands 18.

In order to raise the chute 3 into position, it is provided at its upper end with suitable means for attaching it to a lifting mechanism and, as here shown, with a pair of angle-irons 19, one on each side of the chute 3 opposite to each other and riveted to the strips 17 and each having an ear 20, with an eye 21, riveted to the angle-iron 19. By means of this device a hoisting mechanism, such as the chains 22, may be secured to the eyes 21, the chains 22 being secured to a rope 23, passing over a pulley 24 on the pile-driver and extending to a hoisting-drum. (Not shown.) The chute 3 is independent of and is not connected with the uprights of the pile-driver. It can be swung into and out of position between the uprights of the pile-driver and hoisted, so as to permit the pile to be inserted through its top.

The operation of the device is as follows:

The pile-driver 1 being in position, the chute 3 is hoisted into position by means of the hoisting mechanism, hereinbefore described, between the uprights 2 and is secured in place 5 by lashing or other well-known means. The pile to be driven is then raised by said hoisting mechanism and is lowered into the chute 3, the top of the pile being below the enlarged top of the chute. The pile is then driven by 10 the hammer, and as the pile is driven down the chute 3 may be lowered until its lower end is adjacent to the bottom or substance into which the pile is driven, when the driving of the pile may be continued until the desired position is reached.

While the chute 3 has been shown and described as being separable from and independent of the uprights 2, it is not intended to limit the invention to such construction and arrangement, as the invention broadly contemplates a hammer guide and chute located and secured and adjustable in and removable from the uprights of a pile-driver in any suitable manner.

25 In order to obviate the hoisting of the pile when it is inserted in the chute 3, the latter may have one side hinged, so as to be opened and introduce the pile laterally, as shown in Fig. 5.

30 It will be seen that the chute constructed as herein set forth presents an open framework which is light, strong, durable, and economical.

35 By means of this device piles may be driven under water to a considerable depth, and the necessity of cutting off the end of the pile, as in the old way, obviated.

Having thus described my invention, what I claim, and desire to secure by Letters Patent, is—

40 1. The combination with a pile-driver, of a hammer guide, or chute, independent of the pile-driver, and laterally, and vertically, ad-

justably, and removably connected with the uprights of the pile-driver, as herein set forth. 45

2. The combination with a pile-driver, of a hammer guide, or chute, independent of the pile-driver, and laterally, vertically, adjustably, and removably connected with the uprights of the pile-driver, and means for raising or lowering the hammer guide, or chute in said uprights, as herein set forth.

3. A hammer guide, or chute for pile-drivers, independent of and laterally, and vertically adjustably and removably connected 55 with the uprights of the pile-driver, and consisting of an open framework, formed of guideways for the hammer, and braces, and connections, holding said guideways together, as herein set forth.

4. A hammer guide, or chute for pile-drivers, consisting of a number of sections bolted together, each section formed of guides for a hammer; cross-braces riveted to said guides, and flanged plates connecting the ends 65 of said guides together, and bolted to the adjacent flanged plates, as herein set forth.

5. A hammer guide, or chute for pile-drivers, consisting of an extended open framework, having guides for the hammer, and an 70 enlarged upper end, as herein set forth.

6. A hammer guide, or chute for pile-drivers, independent of and laterally, and vertically adjustably and removably connected with the uprights of the pile-driver, and consisting of an extended open framework, with 75 guides for the hammer, and means for attaching the chute to a hoisting mechanism, as herein set forth.

In testimony whereof I have signed my name 80 to this specification in the presence of two subscribing witnesses.

WILLIAM H. ELLIS.
